SLIP STITCH SEWING MACHINE

Harry Honig and Max Greenfield, New York, N. Y.

Application December 20, 1949, Serial No. 134,004

22 Claims. (Cl. 112—174)

1

The present invention relates to sewing apparatus, more specifically, this invention relates to apparatus for sewing slip stitches, of the type particularly adapted for forming the slip stitch, which loosely and resiliently joins the outer necktie fabric with the necktie lining in a four-inch necktie to permit stretching of the necktie without breaking the stitch.

Apparatus or machines for sewing slip stitches in neckties or the like have heretofore been known and used. However, such apparatus as heretofore used for the slip stitching purposes in the necktie art have had certain shortcomings which detracted from their convenience and desirability. The slip-stitch sewing apparatus heretofore used had very stiff action, by which is meant that the movement of the needle through the material and movement of the material upon the needle was effected with great effort and strain against great resistance, and the material was moved along the needle in substantially flat position; for which reasons the needle had to be of great length, at least as long as the necktie upon which it worked, and had to be firmly and almost rigidly supported in place. Despite the support given the needle, however, breakage of the very long needle of the apparatus of the prior art, with its consequent substantial increase in maintenance cost and costly delays in the work, were frequent occurrences.

Also, both because of the great length of the needle as well as because the operation of the machine against great resistance from the work, the machine had to be of large and bulky size, occupying a great deal of factory space, and of very heavy and rugged construction and supported on specially built heavy and rugged supports, by reason of all of which the initial cost of the machine and its installation as well as its maintenance, was comparatively high.

It is the general object of the present invention to provide a machine for sewing slip stitches, particularly in neckties, which will overcome all of the foregoing disadvantages and shortcomings of the slip stitch sewing machines of the prior art.

It is, thus, one object of the present invention to provide a slip stitch sewing machine of the character described in which the needle penetrates the fabrics sewn by it with great ease and with a minimum of resistance.

It is another object of the present invention to provide a slip stitch sewing machine of the character described in which the material sewn is easily and smoothly moved along the needle also with a minimum of resistance.

2

It is still another object of the present invention to provide a slip stitch sewing machine of the character described which compactly bunches the sewn material upon the needle whereby a much smaller needle may be used.

5 It is yet another object of the present invention to provide a slip stitch machine of the character described which, by reason of lesser needle length and ease and facility of sewing, may be of relatively small size and light weight and construction, occupying a minimum of factory space and supportable on a conventional shop table, if desired.

10 It is also an object of the present invention to provide a slip stitch sewing machine of the character described which positively and mechanically removes the sewn material from the machine with a minimum of strain and effort upon the machine.

15 It is a further object of the present invention to provide a slip stitch sewing machine of the character described in which the needle may remain permanently threaded without the need for rethreading for each individual necktie sewn thereon.

20 It is a still further object of the present invention to provide a slip stitch sewing machine of the character described having novel and improved fabric guiding means which readily and easily guides and positions the several fabrics sewn together in proper relative position for receiving the slip stitch seam.

25 Still further and general objects of the present invention are to provide a slip stitch sewing machine of the character described which, because of its size and weight as well as because of its ease of operation, is economical to produce and economical to maintain; which is strong, durable and rugged and not likely to get out of order; which may be supported on conventional work tables without requiring any specially built supports therefor; and which is easy and convenient to use and operate and greatly reduces the physical and mental strain on the operator.

30 45 The foregoing and other advantages and superiorities of the slip stitch sewing machine of the present invention will become more readily apparent to those skilled in the art from the embodiment thereof shown in the accompanying drawings and from the description following. It is to be understood, however, that such embodiment is shown by way of illustration only, to make the principles and practice of the invention more 50 55 readily comprehensible and without any intent

of limiting the invention to the specific details therein shown.

In the drawings:

Fig. 1 is a side elevational view of the apparatus of the present invention, as viewed from the right of an operator, taken on line 1—1 of Fig. 3;

Fig. 2 is a side elevational view of the same as viewed from the left of the operator;

Fig. 3 is a top plan view of the apparatus, partly broken away and in section, to show details of construction, with the part in broken lines showing the fabric guiding means in open position;

Fig. 4 is a fragmentary, detailed view, partly in section, showing the fabric moving means of the present invention;

Fig. 5 is a section taken on line 5—5 of Fig. 3;

Fig. 6 is a rear end view of the apparatus;

Fig. 7 is a fragmentary, side elevational view of the rear portion of the apparatus showing additional or alternate means for vibrating the sewing needle;

Fig. 8 is a fragmentary, perspective view of the front end of the apparatus illustrating the automatic means for opening the fabric guiding mechanism of the machine;

Fig. 9 is an isometric view of the movable part of the fabric guiding mechanism of the present invention, partly broken away to show details of construction, and

Fig. 10 is a section taken on line 10—10 of Fig. 7.

Generally stated, the slip stitch machine of the present invention consists of a horizontally disposed long needle, means for folding or crimping the fabric and advancing it toward the needle to be pierced and threaded thereby, reversible means for advancing and withdrawing the material along the needle, and means for rocking the needle to facilitate its movement through the fabric, all operable from a single drive, and means for alining and guiding the several fabrics toward the crimping mechanism.

Referring more specifically to the accompanying drawings, the machine of the present invention comprises a frame which may consist of a base 10 and a table 11 having an upper plate 12 mounted thereon and means for spacing and supporting the table upon the base 10 such as the posts 13, 14 and 15.

The driving mechanism of the apparatus may comprise a main shaft 20, suitably journalled, as in spaced posts or brackets 21 and 14, set on the base 10. The shaft 20 is provided at one end, at one edge of the table 11, with a pulley wheel 23, by which it may be connected as by a belt to a driving motor (both not shown), and, inwardly of the pulley wheel 23, with a gear wheel 24. The driving shaft 20 is provided at its opposed end, adjacent the other edge of the table 11, with another gear wheel 25, and inwardly of the gear 25 with a bevelled gear 26.

At the rear of the apparatus there is supported on the base 10, an upright wall 27, in which is journalled a bushing 28 having a square or other polygonal opening therein, in which is slidably keyed or positioned a square or other correspondingly polygonal rod 29 having a knob 30 at its outer end and a socket 31 at its inner end of greater cross section than the bushing opening, in which socket may be secured, by any desired suitable means, a forwardly horizontally extending needle 32, in parallel and slightly raised position relative the upper table plate 12.

The bushing 28 carries exteriorly of the wall 75

27 a gear 33 which meshes with a sector gear 34, fixed on a shaft 35, which may be journalled in a post 36 supported on the wall 27. The sector gear 34 is connected by a link 37 to an eccentric 38 mounted on a shaft 39 journalled with suitable bearings in wall 27 and post 13; the eccentric 38 operating to convert the rotary movement of the shaft 39 into a rocking movement of the bushing 28 of the rod 29, the needle 32, such rocking movement being through an arc of any magnitude less than 360° that may be desired and preferably of about 180°.

The shaft 39 carries on its inner end a bevelled gear 40 by means of which it is operably connected to the main shaft 20 as by a cooperating bevel gear 41 mounted on a shaft 42 which is journalled in a suitable bearing secured in the post 14. The shaft 42 also carries a reduced gear 43 in position to mesh with the end gear 25 on the main shaft 20.

It will be apparent that as the main shaft 20 is rotated the needle actuating shaft 42 will be rotated and the needle 32 rocked at a speed which, because of the reduced size of gear 43, will be greater than the speed of rotation of the shaft 20. Preferably a gear ratio of 1 to 5 may be used to effect the rocking of the needle 32 five times for every revolution of the main shaft 20.

The fabric folding or crimping means may comprise a toothed wheel 45 having evenly spaced teeth 46, all of which are cut approximately at their center by a V-shaped groove 47. The wheel 45 is mounted on a shaft 48 journalled at its ends between the post 15 and a bracket 49 supported on the underside of the lower table plate 11 in position to have the teeth 46 extend through the longitudinal opening 50 formed in the table plates 11 and 12 with the groove 47 in alignment with and its bottom slightly raised above the level of the plate 12 and on a level with the needle 32.

The wheel 45 is operatively associated with the main shaft 20 through a shaft 52 journalled in a bracket or post 53 and having at its inner end a bevel gear 54 meshing with the bevel gear 26 of the main shaft 20. The shaft 52 carries, under the shaft 48, a worm gear 55 which meshes with a gear 56 carried on a shaft 48.

Another toothed wheel 58 of similar construction as the wheel 45 is idly journalled directly above wheel 45 on a horizontal shaft 59 which is set into a block 60 mounted on a square rod 61 which is vertically slidably arranged in a square opening 62 in the block 15. The opening 62 extends through the base 10 and the portion of the rod 61 below the base 10 has a coil spring 63 mounted over it, which spring is retained in place, as by means of a nut 64 engaging the threaded end of the square rod 61 to normally maintain the block 60 in lowermost position, resting on block 15, with the teeth of the wheel 58 meshing with the teeth of the companion crimping wheel 45.

The wheel 45 is geared to have its portion above the table 11 move in a direction toward the needle 32. It will be apparent that one or more layers of fabric which are arranged between the teeth of the wheels 45 and 58 will be crimped or arranged in wave formation between the teeth and advanced by the teeth, as the wheels 45 and 58 are rotated needleward, to have the needle penetrate both sides of each crimp or wave created in the fabric by the crimping wheel teeth.

It will also be apparent that the rapid rocking vibratory or oscillating movement of the needle 32, effected simultaneously with the rotation of

the wheels 45 and 48 and the advancing of the fabric on the needle, will facilitate the penetration of the needle through the fabric as well as the advancing of the fabric on the needle and will enable the accomplishment of both processes with a minimum of strain.

It will be further apparent that, because the needle oscillation does not involve a complete rotation of the needle, the resistance reducing effect of its rocking can be attained without interfering with the pre-threading of the needle, so that the fabric may be actually threaded and stitched as it is moved along the needle, with a double thread stitch of increased strength, if desired, and the need of rethreading the needle for each garment stitched is eliminated. Furthermore the stitched fabric moves easily along the needle in wavy formation and without jamming, so that the operation of the machine is against a continuously constant but low strain, which eliminates needle breakage from any possible jamming of the fabric or over-strain of the machine, without the need for rigid needle support, and generally lightens the work of and the tension upon the operator and permits the use of a much smaller and much lighter machine.

Means are provided for spacing the wheels 45 and 48 apart for the introduction of fabric between them as well as for facilitating the withdrawal of the stitched fabric from the needle 32. Such means may comprise a pulley wheel 66 suitably supported in any desired manner in elevated position relative to the block 60 and a cord, chain or cable 67 passing over the pulley 66, one end engaging the block 60, as by means of the ear 68, on its upper end face; and the other end of the cable 67 connected to manual or pedal depressing means of any desired or suitable conventional type, not thought necessary to be specifically illustrated.

The fabric advancing means for moving and gathering the material of the necktie in folds upon the needle 32 may comprise an endless flexible conveying member, preferably in the form of an endless sprocket chain 70 consisting of links each comprising a pair of spaced plates 71, the overlapping ends of which are connected by pins 72. The sprocket chain 70 is disposed in a slot 73 formed in the table 11 and top plate 12 in alignment with the needle 32 and is supported with one of its parallel lengths below the table 11 and the other above the table 11; the sides of the links fitting relatively snugly between the slot edges in the plate 12 to prevent lateral displacement of the sprocket chain during operation.

The sprocket chain 70 is supported upon a pair of spaced sprocket wheels 75 and 76. One of said sprocket wheels as the rear one 75 may be an idler journaled on a shaft 77 supported in a bracket 78 fixed on the underside of the table 11. The other or forward sprocket wheel 76 may be journaled on a shaft 79 which is likewise supported in a bracket 80 depending from the other side of the table plate 11. The shaft 79 may carry on one end, in alignment with the gear wheel 24, a gear wheel 81.

A third sprocket wheel 83 may engage the sprocket 70 from below, at a point adjacent its center. The sprocket 83 may be supported on a shaft 84 journaled in the post 14, which shaft carries a gear wheel 85 in alignment with the gear wheel 81.

In order to make the sprocket chain operate reversibly from the main driving shaft 20, preferably independently of the wheels 45 and 48 and 75,

of the needle 32, the latter of which may be operated continuously in the same direction, there is provided a bar 87 which is pivoted at its center 88 upon a suitable bracket 89 mounted on the table plate 12. The bar 87 carries at its inner end a shaft 90 supported in an elongated slot 91 of a boss 92 on which shaft 90 is journaled a gear wheel 93 in position between a driving gear wheel 94 meshing with the gear wheel 24 and the gear wheel 85 of the sprocket 83. The bar 87 carries at its forward end a shaft 95 supported in a slot 96 on a boss 97 on which is journaled a second gear wheel 98 in position between the driving gear wheel 94 and the gear wheel 81 of the sprocket 76. The bar 87 has a forwardly extending arm 99 secured thereto which may terminate in a vertical end 100 in which may be formed a vertical slot 101 which is engaged upon the pin 102, which may be set in a side face of the block 60; the slot 101 and slots 91 and 96 permitting ready adjustment of the gear wheels 93 and 98 in proper meshing position.

It will be readily apparent that when the machine is set for sewing, with the block 60 in lowermost position resting on the post 15, the forward end of the rod 87 will be tilted down and its rear end raised so that the gear wheel 98 will operatively engage the gear wheel 81 of the sprocket 76 with the driving gear 94 to cause the sprocket 76 to rotate in the same direction as the wheel 45, namely, to turn the sprocket chain in the direction of the needle to move any material disposed over the sprocket chain and advance it upon the needle; the gear wheel 93 being idle. It will likewise be apparent that when the block 60 is raised, the forward end of the arm 87 will be raised and its rear end lowered, so that gear wheel 98 engages the gear wheel 94 with the gear wheel 85 of the sprocket 83 to operate the sprocket chain in the reverse direction, for removing the necktie fabric from the needle; such operation coinciding with the spacing of the wheels 45 and 48 to permit its carrying out.

It will be noted that the reverse feeding mechanism is operated directly from the main driving shaft 20, while the needle 32 is vibrated to facilitate the movement of the fabric therefrom, and without in any way interfering with the direction of the needle vibration. It will be clear that such arrangement permits the smooth operation of the apparatus and avoids any jarring disturbances of the feeding and needle-vibrating mechanism that might be occasioned if a reversible motor were used for the same purpose.

To ensure engagement between the sprocket chain 70 and any fabric passing thereover so that such fabric will be advanced by it there is provided means for resiliently pressing such fabrics against the sprocket chain 70. Such means comprises a post 105 mounted on the table 11 parallel to the sprocket chain opening or slot 73 and intermediate its ends. A pair of links 106 and 107 are each pivoted by one end at the upper end of the post 105 in parallel relation to the slot 73. Each of the links 106 and 107 carries at its other, lower end a shaft 108 and 109, respectively, extending transversely over the slot 73, each shaft carrying journaled thereon a rubber tired wheel 110 and 111, respectively, in position to ride on the sprocket chain 70. The links 106 and 107 and the wheels 110 and 111 are of such height that the wheels 110 and 111 are spaced apart from one another, preferably one to each side of the post 105.

While the weight of the wheels 110 and 111

may be adequate to provide the desired feeding pressure, additional pressure may be provided by resiliently connecting the shafts 106 and 107 as by the spring 112 to pull the wheels 110 and 111 towards one another and against the sprocket chain 70.

To facilitate the movement of the fabric by the sprocket chain 70 upon the needle 32 suitable feeding teeth may be provided on the sprocket chain. These feeding teeth may be cut in the side plates 11 of the links or may be separately mounted with the link plates upon the link pins 12. For improved operation in the movement of the fabric on to the needle it has been found desirable to provide inwardly feeding teeth 115 on distantly spaced links, as every 10 or 12 links, so that each set of teeth 115 moves not one fold or fabric but a bunch of folds or fabric first under the wheel 110 and then under the wheel 111, maintaining the fabric in bunched folded position throughout the movement for greater ease of such movement. Reverse feeding teeth 116, on the other hand, may be provided on each of the other links of the sprocket chain 70.

It may here be stated that the pressure of the rollers or wheels 110 and 111 also serves to keep the fabric from rocking with the needle, which would nullify the effect of the rocking, and to maintain the fabric in a stationary flat position.

Other means for imparting vibratory movement to the needle 32 during the operation of the machine for the purpose of facilitating its movement into and through the fabric may be provided in lieu of the vibratory rocking movement heretofore described or in addition thereto. Such needle vibrating means is illustrated in Figs. 6 and 7 and comprises an electro-magnetic vibrator 120 mounted on the rearward extension of the base 10. The vibrator 120 is provided with a vibrating or clapper arm 121 which is arranged to strike the knob 30 at the end of the needle rod 29 when such rod is at its extreme rearwardly extended position to give the needle 32 a slight forward movement while the clapper arm 121 is in circuit breaking position. The requisite position of the needle rod 29 for such operation, as will be readily apparent, will occur only when the machine is in stitching operation, when the pressure of the fabric advancing against and on the needle 32 will cause it to withdraw to its rearmost position with the knob 30 in close proximity to the clapper arm 121. Such pressure will also cause the knob 30 to recoil back to vibrator contacting position after each slight forward movement. On the other hand, when the machine is reversed to withdraw the fabric from the needle 32 the forward pull exerted by such withdrawal will cause the needle 32 and the needle rod 29 to be pulled to its extreme forward position, with the knob 30 out of contacting position with the clapper arm 121 of the vibrator 120. It will be clear that the vibratory movement this produces in an axial direction will also permit and in no way interfere with threading of the needle 32 before the slip stitching operation is commenced to permit continuous operation without need for rethreading.

Improved means are also provided with the slip stitching machine of the present invention for the automatic guiding of the necktie fabric and lining, as well as any tape that is sometimes associated with the slip stitch seam, in position to receive the slip stitch seam at the desired and proper place. Such fabric guiding mechanism may comprise a straightforward edge 125 on

the table plates 11 and 12 and a plate 126 mounted on pins 127 between the table 11 and base 10; the plate 126 being provided with a concave forward edge 128 formed, preferably, by a central flat edge portion and outwardly tapering side edge portions.

The fabric guiding means comprises, further, a gate member, generally designated as 130, of approximately rectangular shape, which is pivoted at an inner corner on a pin or post 131 set into the base 10 adjacent the post 15. The gate 130 may be formed of a plurality, such as three, of spaced superposed plates, namely, an upper plate 133, an intermediate plate 134, and a bottom plate 135, all secured to one another in spaced apart position by connecting and spacing pins, such as 136, set into their corners.

The upper plate 133 may be arranged to lie substantially parallel with the table 11 and may be formed with a slightly concave inner edge 138, and with an inwardly tapering recess or depression 139 at its center adapted to serve as a guide for a tape, if one is used. A cover plate 140 may be provided over the recess 139 and hinged, as at 141, to the plate 133 to cover the recess 139 and to bring the level of the plate 133 approximately even with the surface of the plate 12.

The plate 134 may be wider than the plate 133 with its width increase arranged to project inwardly of plate 133 and it may be arranged so that its portion projecting inwardly extends into the space between the table 11 and the guide plate 126 to overlap the latter. The plate 135 may be similar in size and arrangement to the plate 134 and may be positioned to extend under the plate 126 when the gate 130 is in closed position.

The inner edges of both plates 134 and 135 may be concave, similar to but in reverse direction to the edge 128 of the plate 126.

In operations, the lining and face fabric of the necktie are placed between the inner edge of the gate 130 and the forward edge of the machine. The overlapping edges of plates 126, 134 and 135 will dispose the fabrics in zig-zag formation, to create a frictional drag upon them while the concave edges of the latter three plates will tend to center and dispose the fabrics in proper position for accurately receiving the slip stitch where desired. Where a tape is used, such tape may be separately placed in the depressed recess 139 in the plate 133 and fed therethrough, together with the face and lining fabric, to the crimping wheels 45 and 48.

Means may be provided for automatically normally keeping the gate 130 in closed position and for automatically opening the gate after one necktie is slip-stitched for the insertion of the fabrics of the following necktie for slip stitching. Such means may include a coil spring 143 mounted over the hinge pin 131 to normally resiliently urge the gage towards closing position, and a downwardly and forwardly tapering nose or cam 144 mounted on the forward face of the block 60, the upper or cam edge 145 of which may engage against the inner edge of the gate 130. The cam 144 may be so arranged and shaped that when its supporting block 60 is in lowermost position with the wheels 45 and 46 meshing for slip stitch operation the edge of the gate 130 will ride on the upper portion of the cam edge 145, permitting it to remain in closed position in response to pressure from the spring 143. However, when the block 60 is raised to reverse the operation of the machine from slip stitching to the removal of the slip stitched neck-

tie the nose or cam 144 will be raised with it, its cam edge 145, as it rises, pushing the gate 130 into open position, as indicated by the broken lines in Fig. 3, in readiness for insertion of fresh fabrics.

This completes the description of the construction and operation of the slip stitching machine of the present invention. It will be clearly seen that this slip stitching machine, by reason of the vibration of the needle either in a plane perpendicular to its long axis or parallel to its long axis or both, as well as by reason of its novel fabric advancing mechanism makes the operation of the machine light and easy and against a minimum of strain and resistance and permits the compact gathering of the slip stitch fabric upon the needle thereby making possible a smaller and more compact machine of lighter weight yet rugged, more durable and less likely to go out of order by reason of needle breakage or from operational strain.

It will also be seen that the slip stitch machine of the present invention, because of its positive reversible fabric moving mechanism, makes the operation of slip stitching more rapid and easier upon the operator.

It will also be apparent that the fabric guiding mechanism of the machine of the present invention further speeds, simplifies and facilitates the work of the operator of the machine.

It will likewise be apparent that the machine of the present invention by reason of having all of its several mechanisms, performing its several operations, have a common drive and common means for synchronously setting them into operation, is of highly simplified construction utilizing a minimum number of parts likely to get out of order and is compact and, therefore, economical as well as easy to produce, use and maintain.

It will further be apparent that numerous variations and modifications may be made in the slip stitch machine of the present invention in accordance with the principles hereinabove set forth, without the use of any inventive ingenuity. We desire, therefore, to be protected for any and all such variations and modifications that may be made within the spirit of the present invention and the scope of the claims hereto appended.

What we claim is:

1. A slip stitch sewing machine comprising a needle, means mounting said needle at one end in a horizontal position for reciprocatory and oscillating movement, a toothed crimping wheel having a circumferential groove formed thereon through the teeth thereof mounted forwardly of said needle in position to receive the free end of said needle in the groove thereof, a cooperating toothed crimping wheel having a circumferential groove formed through the teeth thereof, means for supporting said second crimping wheel in displaceable relation to said first crimping wheel, a main driving shaft adapted to be connected to a source of power, means operatively connecting said first crimping wheel to said main driving shaft for rotation of said first crimping wheel and means for oscillating said needle.

2. A slip stitch sewing machine comprising a needle oscillatably mounted by one end in horizontal position, a toothed crimping wheel having a circumferential groove formed thereon through the teeth thereof mounted forwardly of said needle in position to receive the free end of said needle in the groove thereof, a cooperating toothed crimping wheel having a circumferential groove formed through the teeth thereof, means for supporting said second crimping wheel in displaceable relation to said first crimping wheel, rotary main shaft adapted to be connected to a source of power, means operatively connecting said first crimping wheel to said driving shaft for rotation of said crimping wheel, and means operatively connecting said needle to the said main driving shaft for oscillation of the said needle in a plane perpendicular to the longitudinal axis thereof through an angle of less than 360°, when said first crimping wheel is rotated, at a speed ratio greater than the speed of rotation of said first crimping wheel.

for supporting said second crimping wheel in displaceable relation to said first crimping wheel, a main driving shaft adapted to be connected to a source of power, means operatively connecting said first crimping wheel to said main driving shaft for rotation of said first crimping wheel, means for oscillating said needle and means operatively connected with said main driving shaft for advancing a fabric on said needle including a continuous conveyor member underlying said needle and resiliently pressed rotary elements overlying said needle.

3. A slip stitch sewing machine comprising a needle, means mounting said needle at one end in a horizontal position for reciprocatory and oscillating movement, a toothed crimping wheel having a circumferential groove formed thereon through the teeth thereof mounted forwardly of said needle in position to receive the free end of said needle in the groove thereof, a cooperating toothed crimping wheel having a circumferential groove formed through the teeth thereof, adapted to mesh with said first crimping wheel, means for supporting said second crimping wheel in displaceable relation to said first crimping wheel, a main driving shaft adapted to be connected to a source of power, means operatively connecting said first crimping wheel to said driving shaft for rotation of said first crimping wheel, and means operatively connecting said needle to the said main driving shaft for oscillation of the said needle when said first crimping wheel is rotated.

4. A slip stitch sewing machine comprising a needle oscillatably mounted in horizontal position, a toothed crimping wheel having a circumferential groove formed thereon through the teeth thereof mounted forwardly of said needle in position to receive the free end of said needle in the groove thereof, a cooperating toothed crimping wheel having a circumferential groove formed through the teeth thereof and adapted to mesh with said first crimping wheel, means for supporting said second crimping wheel in displaceable relation to said first crimping wheel, main shaft adapted to be connected to a source of power, means operatively connecting said first crimping wheel to said driving shaft for rotation of said first crimping wheel, and means operatively connecting said needle to the said main driving shaft for oscillation of the said needle in a plane perpendicular to the longitudinal axis thereof through an angle of less than 360° when said first crimping wheel is rotated.

5. A slip stitch sewing machine comprising a needle oscillatably mounted in horizontal position, a toothed crimping wheel having a circumferential groove formed thereon through the teeth thereof mounted forwardly of said needle in position to receive the free end of said needle in the groove thereof, a cooperating toothed crimping wheel having a circumferential groove formed through the teeth thereof, means for supporting said second crimping wheel in displaceable relation to said first crimping wheel, rotary main shaft adapted to be connected to a source of power, means operatively connecting said first crimping wheel to said driving shaft for rotation of said crimping wheel, and means operatively connecting said needle to the said main driving shaft for oscillation of the said needle in a plane perpendicular to the longitudinal axis thereof through an angle of less than 360°, when said first crimping wheel is rotated, at a speed ratio greater than the speed of rotation of said first crimping wheel.

6. A slip stitch sewing machine comprising a needle mounted horizontally by one end for sliding and rotary movement, a wheel having circumferentially disposed crimping teeth and a groove formed through said crimping teeth mounted forwardly of said needle in position to receive the free end of said needle in the said groove, a cooperating wheel having crimping teeth and a groove formed through said crimping teeth and adapted to mesh with said first wheel, means for supporting said second wheel in displaceable relation to said first wheel, a main rotary driving shaft adapted to be connected to a source of power, means operatively connecting said first wheel to said main driving shaft for rotation of said crimping wheel, means for oscillating said needle and means for advancing a fabric on said needle including an endless conveyance member underlying and parallel to said needle in position to have said needle rest thereon, and operatively connected to said main driving shaft, and a pair of pivotally mounted downwardly diverging roller members overlying said needle and resilient means connecting said roller members for urging them towards one another and against said needle.

7. A slip stitch sewing machine comprising a needle mounted horizontally by one end for sliding and rotary movement, a wheel having circumferentially disposed crimping teeth and a groove formed through said crimping teeth mounted forwardly of said needle in position to receive the free end of said needle in the said groove, a cooperating wheel having crimping teeth and a groove formed through said crimping teeth and adapted to mesh with said first wheel, means for supporting said second wheel in displaceable relation to said first wheel, a main rotary driving shaft adapted to be connected to a source of power, means operatively connecting said first wheel to said main driving shaft for rotation of said crimping wheel, means for oscillating said needle and means for advancing a fabric on said needle comprising an endless conveyance member underlying said needle, means for reversibly moving said conveyance member and means operated from said second wheel supporting means for operatively connecting said conveyance member moving means to said driving shaft for movement in selected direction, and a pair of pivotally supported downwardly diverging, roller elements overlying said needle and resilient means connecting said roller members for urging them towards one another and against the said needle.

8. A slip stitch sewing machine comprising a needle mounted horizontally by one end for sliding and rotary movement, a toothed crimping wheel having a circumferential groove formed through the teeth thereof mounted forwardly of said needle in position to receive the free end of the needle in the said groove, a main driving shaft adapted to be connected to a source of power, means operatively connecting said crimping wheel to said driving shaft for rotation of the said crimping wheel, a second toothed crimping wheel having a circumferential groove formed through the teeth thereof, means for supporting said second toothed wheel including a block and means for supporting said block for movement in a plane perpendicular to the long axis of the said needle, resilient means for normally maintaining said block in lowermost position with the said second crimping wheel meshing with the said first crimping wheel, means for raising said block for spacing said crimping wheels, means operatively connected with the said driving shaft for oscillating said needle, means for moving the fabric along said needle including an endless conveyor underlying and parallel to said needle and positioned to have said needle rest thereon, a pair of reversible

spacing said crimping wheels, means operatively connected with the said driving shaft for oscillating said needle in a plane perpendicular to its longitudinal axis and through an angle of less than 360° when said first crimping wheel is rotated, means for moving a fabric along said needle including an endless sprocket chain underlying and parallel to said needle and positioned to have said needle rest thereon and means connected to said block and operable by the movement thereof for operatively engaging said sprocket chain with said driving shaft for movement in selected direction, a pair of roller elements pivotally supported in downwardly diverging direction over said needle and resilient means connecting said roller members for movement towards one another and against said needle.

9. The slip stitch sewing machine of claim 8 wherein spaced selected links of the said sprocket chain are formed with teeth facing the direction of the supported end of the said needle.

10. The slip stitch sewing machine of claim 8 wherein selected spaced links of the said sprocket chain are formed with teeth facing in the direction of the supported end of the said needle and other links of the said sprocket chain are formed with teeth facing in the direction of the free end of said needle.

11. The slip stitch sewing machine of claim 8 wherein said means for moving said sprocket chain comprises a pair of sprockets engaging said chain from the inside thereof, one of said sprockets being an idler and the other of said sprockets being a driver and carrying a gear wheel therewith, a third sprocket carrying a gear wheel therewith engaging said sprocket chain from below, a driving gear wheel on said driving shaft, a second gear wheel engaging said driving gear wheel, a pair of idler gear wheels mounted on a tiltable support in position to have one of them interengage said second gear wheel with the gear wheel carried with said third sprocket when said idler gear wheel support is tilted in one direction and to have the other of said idler gear wheels engage said second gear wheel with the gear wheel of said second sprocket when the said support is tilted in the other direction, and means connected to said block and operated by the movement of said block for tilting said idle gear support in selected direction.

12. A slip stitch sewing machine comprising a needle mounted horizontally by one end for sliding and rotary movement, a toothed crimping wheel having a circumferential groove formed through the teeth thereof mounted forwardly of said needle in position to receive the free end of the needle in the said groove, a main driving shaft adapted to be connected to a source of power, means operatively connecting said crimping wheel to said driving shaft for rotation of the said crimping wheel, a second toothed crimping wheel having a circumferential groove formed through the teeth thereof, means for supporting said second toothed wheel including a block and means for supporting said block for movement in a plane perpendicular to the long axis of the said needle, resilient means for normally maintaining said block in lowermost position with the said second crimping wheel meshing with the said first crimping wheel, means for raising said block for spacing said crimping wheels, means operatively connected with the said driving shaft for oscillating said needle, means for moving the fabric along said needle including an endless conveyor underlying and parallel to said needle and positioned to have said needle rest thereon, a pair of reversible

driving members engaging said endless conveyor from opposed sides and means connected to and operable from the movement of said block for selectively engaging one of said driving members with the main driving shaft, and a pair of roller elements pivotally supported in downwardly diverging direction over said needle and resilient means connecting said roller members for movement towards one another against said needle.

13. A slip stitch sewing machine comprising an elongated needle having an eye at one end, means for supporting said needle by its other end for sliding and rotary movement including a rotatably supported bushing, a rod having the needle socket at one end keyed for slidable movement within said bushing, a main rotary driving shaft adapted to be connected to a source of power, a gear wheel on said bushing, a rocker arm meshing with said bushing gear wheel, an eccentric mounted on a rotary shaft, a link connecting said rocker arm with said eccentric and means operatively connecting said rotary shaft to said main driving shaft, a toothed crimping wheel having a circumferential groove formed therein through the tooth thereof mounted adjacent the free end of said needle in position to receive said end in the said groove, a second similar cooperating crimping wheel, means for supporting said second crimping wheel in displaceable relation relative to said first crimping wheel and means for moving a fabric along said needle including an endless conveyor underlying said needle and operatively connected to said driving shaft and a pair of independently mounted roller elements over said needle and means for resiliently pressing said roller elements against said needle.

14. A slip stitch sewing machine, comprising a needle supported by one end for limited movement in the plane of its long axis and for rotary movement in a plane perpendicular to its long axis, means adjacent the free end of said needle for folding a fabric and feeding said folded fabric upon the free end of the needle, reversible means for moving a fabric along said needle, means for rotatably oscillating said needle in a plane perpendicular to the long axis of the needle, through an angle less than 360°, a main rotary driving shaft adapted to be connected to a source of power, and means operatively connecting said fabric folding means, said fabric moving means, and said needle oscillating means to said driving shaft.

15. A slip stitch sewing machine, comprising a needle supported by one end for limited movement in the plane of its long axis and for rotary movement in a plane perpendicular to its long axis, means adjacent the free end of said needle for folding a fabric and feeding said folded fabric upon the free end of the needle, reversible means for moving a fabric along said needle, means for rotatably oscillating said needle in a plane perpendicular to the long axis of the needle, through an angle less than 360°, a main rotary driving shaft adapted to be connected to a source of power, means operatively connecting said fabric folding means, said fabric moving means, and said needle oscillating means to said driving shaft, and means for simultaneously inactivating said fabric folding means and reversing said fabric moving means.

16. A slip stitch sewing machine, comprising a needle supported by one end for limited movement in the plane of its long axis and for rotary movement in a plane perpendicular to its long axis, means adjacent the free end of said needle for folding a fabric and feeding said folded

fabric upon the free end of the needle, reversible means for moving a fabric along said needle, means for rotatably oscillating said needle in a plane perpendicular to the long axis of the needle, through an angle less than 360°, a main rotary driving shaft adapted to be connected to a source of power, means operatively connecting said fabric folding means, said fabric moving means, and said needle oscillating means to said driving shaft, and means for guiding a fabric to said fabric folding means.

17. A slip stitch sewing machine, comprising a needle supported by one end for limited movement in the plane of its long axis and for rotary movement in a plane perpendicular to its long axis, means adjacent the free end of said needle for folding a fabric and feeding said folded fabric upon the free end of the needle, reversible means for moving a fabric along said needle, means for rotatably oscillating said needle in a plane perpendicular to the long axis of the needle, through an angle less than 360°, a main rotary driving shaft adapted to be connected to a source of power means operatively connecting said fabric folding means, said fabric moving means, and said needle oscillating means to said driving shaft, and means for guiding a fabric to said fabric folding means, said guiding means comprising a table forwardly of said fabric folding means, said table having a substantially straight transverse forward edge and at least one plate supported below said table in spaced parallel relation thereto and projecting forwardly thereof, and a guiding gate pivotally supported by one corner adjacent a corner of said table for rotation in a plane parallel to said table, said gate comprising a top plate on a level with said table and having a slightly curved edge facing said table edge and at least two plates supported in spaced parallel relation below said top plate and projecting forwardly of the curved edge thereof and in position to overlap said under-the-table plate, said under-the-table plate and said lower gate plates having curved facing edges.

18. The slip stitch sewing machine of claim 17 wherein the curved edges of said plates are concave.

19. A slip stitch sewing machine, comprising a needle supported by one end for limited movement in the plane of its long axis and for rotary movement in a plane perpendicular to its long axis, means adjacent the free end of said needle for folding a fabric and feeding the folded fabric upon the free end of the needle, reversible means for moving a fabric along said needle, means for rotatably oscillating said needle in a plane perpendicular to the long axis of the needle, through an angle less than 360°, a main rotary driving shaft, adapted to be connected to a source of power, means operatively connecting said fabric folding means, said fabric moving means and said needle oscillating means to said driving shaft, means for guiding a fabric to said fabric folding means, said guiding means comprising a table forwardly of said fabric folding means, said table having a substantially straight forward transverse edge and a guiding gate pivotally supported by one corner adjacent a corner of said table for rotation in a plane parallel to said table, said gate comprising a top plate on a level with said table and resilient means for normally holding said table with an edge of said top plate contiguous to said table edge, said table and said gate each having plates supported thereunder in spaced parallel relation thereto and projecting

therefrom in position to overlap when said gate is in closed position, said plates having their overlapping edges concavely shaped, and means for simultaneously inactivating said fabric folding means, reversing said fabric moving means and swinging said guiding gate away from said table.

20. A slip stitch sewing machine, comprising a needle supported by one end for limited movement in the plane of its long axis, means adjacent the free end of said needle for folding a fabric and feeding said folded fabric upon the free end of the needle, reversible means for moving a fabric along said needle, means for oscillating said needle in the plane of its long axis when said needle is in its extreme withdrawn position, a main rotary driving shaft adapted to be connected to a source of power and means operatively connecting said fabric folding means and said fabric moving means to said driving shaft.

21. A slip stitch sewing machine, comprising an elongated needle having an eye at one end, means mounting said needle at its other end in a horizontal position for reciprocable and oscillatory movement, means for folding a fabric in wave-like folds and simultaneously advancing said folded fabric upon the free end of said needle,

a driving shaft adapted to be connected to a source of power, means operatively connecting said fabric folding and advancing means to said main driving shaft, and means for oscillating said needle.

22. A slip stitch sewing machine, comprising a needle having an eye at one end, means mounting said needle at its other end in a horizontal position for reciprocable and oscillatory movement, 10 a driving shaft, means progressively crimping a fabric and simultaneously advancing said crimped fabric onto the free end of said needle, said fabric crimping and advancing means operatively connected to said driving shaft, and means operatively connecting said needle to said driving shaft for oscillating said needle simultaneously with the operation of said fabric crimping and advancing means.
